UNITED STATES PATENT OFFICE.

JOHN STEWART DUNBAR, OF SUMTER, SOUTH CAROLINA.

DESIGN FOR AN ARTICLE OF MANUFACTURE.

47,556.

Specification for Design.

Patented July 13, 1915.

Application filed April 2, 1915. Serial No. 18,844. Term of patent 7 years.

To all whom it may concern:

Be it known that I, JOHN STEWART DUNBAR, a citizen of the United States, residing at Sumter, in the county of Sumter and State of South Carolina, have invented a certain new, original, and ornamental Design for an Article of Manufacture, of which the following is a specification, reference being had to the accompanying drawing.

The figure is a face view showing my new design for an article of manufacture.

I claim:

The ornamental design for an article of manufacture, as shown.

In testimony whereof I hereunto affix my signature in the presence of two witnesses.

JOHN STEWART DUNBAR.

Witnesses:

H. R. VAN DEVENTER,
EDNA ISLER.
